E. R. FALKENBERG

DRAPERY SUPPORTING DEVICE

Filed Sept. 5, 1922

FIG. 1.

FIG. 2.

FIG. 3.

FIG. 4.

FIG. 5.

UNITED STATES PATENT OFFICE.

ERNEST R. FALKENBERG, OF CHICAGO, ILLINOIS.

DRAPERY-SUPPORTING DEVICE.

Application filed September 5, 1922. Serial No. 586,183.

To all whom it may concern:

Be it known that I, ERNEST R. FALKENBERG, a citizen of the United States, residing at Chicago, in the county of Cook and 5 State of Illinois, have invented a new and useful Improvement in Drapery-Supporting Devices, of which the following is a specification.

My invention relates more particularly to 10 devices for supporting draperies at windows or openings between rooms, and more especially to devices for supporting draperies in pleated condition.

The producing of pleated draperies, in accordance with the practice now commonly employed and in connection with the use of devices as hitherto employed, is a relatively tedious and expensive operation as the material laid into pleat form is required to be 20 sewed in place.

In this connection it is one of my objects to provide a novel, simple and inexpensive construction of drapery-supporting means whereby the material may be quickly manipulated into pleated condition and in such condition quickly and permanently secured in place by a pin, as distinguished from the sewing operation; and to permit this to be done by one who is relatively unskilled in 30 the art of sewing or drapery manufacture.

At openings between rooms where it is desired to arrange drapery, it is common practice to provide a duplex arrangement of draperies or, in other words, hang one drapery at each side of the curtain pole from 35 which they are hung, which makes a double drapery, it being my object in this connection to produce, by a novel and simple operation, draperies of this character.

Referring to the accompanying drawing: 40 Figure 1 is a face view of the upper portion of a part of a pleated drapery supported from a curtain pole, a portion only of which is shown by means constructed in accordance with my invention, a part of the drapery being broken away to disclose certain details of the said means. Figure 2 is a cross-sectional view taken through the supporting curtain-pole and duplex draperies supported 45 at opposite sides of the curtain pole by means in accordance with my invention as shown in Fig. 1. Figure 3 is an enlarged section taken at the line 3—3 on Fig. 1 and viewed in the direction of the arrows. Figure 4 is a 50 broken rear view of a drapery pleated over, and secured to, the means constituting an-

other embodiment of my invention and illustrated therein; and Figures 5 are fragmentary perspective views of the plate 9 shown in Fig. 4, and the clip cooperating therewith.

Referring to the construction of supporting device disclosed in Figs. 1, 2 and 3, it comprises a plate 6 which may be of metal or any other suitable material from which a series of strap portions 7 are struck up, these series extending lengthwise of the plate 65 which latter is shown as of general rectangular form and preferably of a width equal to substantially the width of the pleat to be formed. The striking up of the portions 7 causes the member 6 to present a 70 series of openings which are in alignment in a plane substantially parallel with the plane of the member 6, adapting a pin, or preferably pins, to be threaded therethrough to extend generally lengthwise of the plate and 75 pin to the latter the drapery applied to the member 6 and folded into pleated condition.

In using the member 6, it is applied at the surface thereof opposite that at which the straps 7 extend, against the rear surface of the 80 drapery, as, for example, that represented at 8 and preferably at such a point thereon that its upper edge will be below the upper edge of the drapery. The portions of the drapery at opposite edges of the member 6 are then 85 folded backwardly over these edges to cause the drapery to extend at the rear surface of the member 6, but preferably only part way across this surface and then folded upon itself to extend in opposite directions, thereby forming the drapery into pleated condition as shown. The operator then presses the pleated portions of the drapery into the 90 spaces between the adjacent strap portions 7, as represented of the drapery at 9, to cause portions thereof to extend into line with the 95 openings provided by the straps 7, and pins 10 are thereupon threaded through the openings provided by the strap portions 7 and through the deflected portions 8 of the drapery, thereby pinning the drapery in 100 pleated condition to the member 6. Any suitable form of pin may be used, it being preferred, however, that one having a double point, as shown of the pins illustrated, be provided, the body of the pin between its 105 pointed extremities being formed into a loop portion 11 adapting the pins to be readily applied to position. It is preferred that double pointed pins be used, as thereby these pins may be adjusted to imbed their oppo-

site pointed extremities in the drapery to extend between folded portions thereof as shown more particularly in Figs. 1 and 2.

It will be understood that the plate member 6 would be provided of a number corresponding to the number of pleats it is desired be presented by the drapery, the operator positioning the plates 6 along the upper edge of the drapery and folding the latter upon these plates to produce the pleated effect, at the desired points.

The supporting means also comprises a device for supporting the plate 6, as from a curtain pole represented at 12. In this connection it may be stated that the supporting device for the member 6 is preferably provided, as shown, for supporting a pair of plates 6 located at opposite sides of the curtain pole 12 and connected with the members of a pair of draperies, one of the draperies being disposed at one side of the curtain rod 12 and the other at the other side thereof. The supporting member for the opposed plates 6 comprises a clip 13 of general U-shape in cross-section, adapting it to be applied to straddling position upon the curtain rod 12, the arms of the clip 13 terminating in upwardly-extending hook portions 14 over which the plates 6 at their upper strap portions 7 are adapted to be hooked as represented in the drawings.

The various parts of the structure described are so constructed and arranged, and the draperies 8 so assembled with the members 6 that the upper edges of the pleated draperies extend above the curtain pole 12 a sufficient distance to conceal the latter to view.

The construction shown in Figs. 4 and 5 and provided for the same purpose as that shown in the preceding figures, instead of providing a single series of strap portions, as explained of the preceding structure, the plate member provided and which is represented at 15 and corresponds with the plates 6, is formed at opposite edges with strap portions 16 and 17 which are arranged in pairs, with each pair spaced from each other as shown, the spaces provided being represented at 18, the straps forming each pair being oppositely deflected, as represented, whereby a series of openings is provided at each side of the member 15, the openings of each series extending lengthwise of the member 15 to adapt a pin to be threaded therethrough and in such position extend lengthwise of the member 15.

In the use of the member 15 the latter is applied to the rear face of the drapery represented at 19, and the latter folded rearwardly about the opposite vertical edges of the member 15 and thence folded outwardly in opposite directions as explained of the drapery 8. There is thus provided in line with each of the series of openings pre-

sented by the strap members 16 and 17, folded portions of the drapery, as represented at 20, it being preferred that these folded portions be positioned to extend over the upper and lower pairs of the straps 16 and 17 and behind the intermediate pairs of these straps as shown in Fig. 4. This arrangement just described is not necessary. The drapery pleated to the member 15 would be secured in place thereon as by means of the pins 21 threaded through the openings provided by the straps 16 and 17 and through the portions of the drapery 19 adjacent these straps and those portions extending between the several pairs of straps. 80

The supporting means of Figs. 4 and 5 also comprise a member represented at 22 and which would correspond with the member 13 and be of the same construction as the latter except that instead of providing a single hook 14 at each of its depending arms, as described of the construction shown in Figs. 1, 2 and 3, a double hook, represented at 23, is provided adapted to hook through the strap portions 16 of the intermediate pair thereof and which are exposed at the rear surface of the drapery. 90

It will be understood from the foregoing description that drapery-supporting means constructed in accordance with my invention are not only of simple and economical construction, but by their use draperies may be pleated and hung in place in pleated condition, without requiring any particular skill, and in a comparatively short length of time. 100

While I have illustrated and described certain particular constructions constituting an embodiment of my invention, I do not wish to be understood as intending to limit it thereto as the invention may be embodied in other forms and the particular embodiment shown may be variously modified and altered without departing from the spirit of my invention. 105

What I claim as new, and desire to secure by Letters Patent, is:

1. The combination of a member, a drapery folded about said member into pleated condition, with a portion of said drapery extending entirely across one side of said member, and a pin separate from said member and extending through folded parts of said drapery and interlocked with said member. 115

2. The combination of a member, a drapery folded about said member into pleated condition thereon, said drapery extending entirely across one side of said member and having folded portions at the opposite side thereof located at opposite sides of the median line of said member, and pins separate from said member and extending through the pleats thus provided and interlocked with said member. 120

3. A pleat gauging and supporting de- 130

vice comprising, in combination, a member of substantially the width of the desired pleat, a plurality of laterally offset portions upon said member to provide a series 5 of vertically aligned and spaced apart openings of a size to receive a pin and a supporting hook whereby a pin may be passed through said openings and through a plurality of portions of drapery folded about 10 said member and protruding into the plane of said openings and a supporting hook may be engaged with one of said offset portions.

4. A pleated drapery supporting device 15 comprising, in combination, a member of substantially the width of the desired pleat, a plurality of laterally offset portions upon said member to provide a series of aligned spaced apart openings to receive a pin passing through a plurality of portions of the drapery protruding into the openings, and a supporting hook coacting with one of said offset portions to support the member with its attached drapery.

25 5. Drapery supporting means comprising in combination, a member adapted to be enclosed by a pleat, a plurality of laterally offset portions upon said member to provide a series of vertically aligned and spaced apart openings whereby a pin may be passed through said openings and through a plurality of portions of the drapery protruding between pairs of said offset portions, a hanger adapted to be supported by a curtain pole, and a hook upon said hanger adapted to engage one of said offset portions 35 to support a drapery secured thereto.

6. Drapery-supporting means comprising a member adapted to be applied to straddling position to a curtain pole upon which draperies are to be supported at opposite

sides thereof, members adapted for the folding thereupon into pleated condition of the draperies to be supported, means for securing the draperies in pleated condition upon 45 said second-referred-to members, and means whereby said second-named members are releasably supported at the opposite sides of said first-referred-to members.

7. Drapery-supporting means comprising 50 a member adapted to be applied to straddling position to a curtain pole upon which draperies are to be supported at opposite sides thereof and having hook portions at opposite sides thereof, and members adapted for folding thereupon into pleated condition of the draperies to be supported and adapted to be engaged with said hook portions for supporting said second-named members in position.

8. Drapery-supporting means comprising 55 a member adapted to be applied to straddling position to a curtain pole upon which draperies are to be supported at opposite sides thereof, said member being provided 60 at opposite sides thereof with upwardly-extending hook portions, members adapted for the folding thereupon, into pleated condition, of the draperies to be supported, said second-named members each containing a 65 series of straps presenting a series of openings extending lengthwise of said member and so disposed that a pin inserted therein and through the folded drapery will extend lengthwise of said last-referred-to member, said last-named members being adapted 70 to be supported from said first-named member by engagement of the hooks on the latter with certain of the straps on said second-named members.

75 ERNEST R. FALKENBERG.
